UNITED STATES PATENT OFFICE.

WADE W. BOWMAN, OF NEW YORK, N. Y.

TOWEL-HOLDER.

1,386,761.

Specification of Letters Patent. Patented Aug. 9, 1921.

Application filed February 15, 1917. Serial No. 148,714.

To all whom it may concern:

Be it known that I, WADE W. BOWMAN, residing at New York, in the county and State of New York, have invented certain 5 new and useful Improvements in Towel-Holders, of which the following is a specification.

This invention relates to a towel holder of the type adapted to contain a supply of 10 toweling material and from which an operator may obtain an unused section at will, and by means of which the used sections are automatically returned into the holder by the act of withdrawing the unused sections.

15 The object of the invention is to provide improved and more efficient mechanism for producing the above results.

A more detailed object is to provide improved means whereby a ribbon like tape of 20 toweling material may be readily and quickly threaded through the device.

A further object is to provide improved and more efficient means whereby the passage of the toweling material through the device will more effectively and correctly operate the automatic take-up.

A further object is to provide an improved form of support for one of the friction rollers employed.

30 A further object is to provide means whereby the operation of the automatic take-up is rendered adjustable.

A further object is to provide a casing in which the supply of unused toweling is contained within a compartment separate and distinct from the compartment containing the used portions of the toweling.

A further object is to provide improved means for mounting the roller upon which 40 the used portions of the toweling is wound.

A further object is to provide an improved form of casing in which the various parts of the mechanism are contained and to provide means whereby the parts of the casing 45 may be readily assembled.

A further object is to provide an improved type of bearing adapted for use in supporting certain of the rollers, etc., in the device.

50 Other objects and aims of the invention, more or less specific than those referred to above, will be in part obvious and in part pointed out in the course of the following description of the elements, combinations, 55 arrangements of parts and application of principles, constituting the invention; and

scope of protection contemplated will be indicated in the appended claims.

In the accompanying drawings, which are to be taken as a part of this specification, 60 and in which I have shown merely a preferred form of embodiment of the invention:

Figure 1 is a vertical transverse sectional view through a towel holder constructed in 65 accordance with this invention, said view illustrating by dotted lines the manner of threading the toweling material into position.

Fig. 2 is a vertical sectional view taken 70 upon the plane of line II of Fig. 1 and looking in the direction of the arrow.

Fig. 3 is a horizontal sectional view taken upon the plane of line III of Fig. 1.

Fig. 4 is a diagrammatic perspective view 75 illustrating the manner of assembling the parts of the casing.

Fig. 5 is an enlarged detail view of a portion of one of the friction rollers employed, a portion of the view being shown in section 80 upon the plane of line V of Fig. 6.

Fig. 6 is a transverse sectional view, taken upon the plane of line VI of Fig. 5.

Fig. 7 is a side elevational view, partly in section, illustrating the construction of 85 one of the resilient members of the supporting frame for one of the friction rollers.

Fig. 8 is an edge view of the structure shown in Fig. 7.

Fig. 9 is an elevational view of one of 90 the improved bearings employed, and

Fig. 10 is a transverse sectional view taken upon the plane of line X of Fig. 9.

Fig. 11 is a slightly enlarged fragmentary detail view of the guiding and control 95 device employed.

Referring to the drawings for describing in detail the structure which is illustrated therein, the reference character L illustrates the outer member of the casing. The reference character G indicates the inner member of the casing.

Both the inner and outer members of the casing may be made of any desired material, or of any size, etc., as may be found appropriate in use. As illustrated, however, they are both formed of sheet metal.

The outer member L is of rectangular box-like form having a back wall 1, and top, bottom and side walls 2. The front wall as 110 3, is hinged to the forward edge of one of the side walls and constitutes a door

which may be swung into and out of position closing the otherwise open front side of the casing.

At the top and bottom front edges of the part L are formed openings or guideways 4 into which the inner member of the casing may be slid when assembling parts, as clearly indicated in Fig. 4.

The inner member G is made up essentially of two vertical plates, 5 and 6, connected together by a horizontal plate 7. The plates 5 and 6 directly support all of the rolls and other moving parts of the mechanism and after said parts are adjusted into position upon said plates, the plates with said parts, are moved into the main casing through the guideways 4. The rear edges of the plates 5, 6 and 7 abut against the inner surface of the rear wall 1 of the main casing, and tangs 8, which are carried at the rear edges of the plates 5 and 6, are projected through mating apertures formed in the rear wall 1 and are bent over as at 9, as clearly seen in Fig. 3. By this means, the inner, or auxiliary, casing is thus held rigidly within the outer, or main, casing.

The plates or walls comprising the inner casing are of such size that their marginal portions fit snugly against the adjacent portions of the main casing and thereby serve to reinforce the main casing.

The horizontal plate 7 of the inner casing positively divides the device into an upper compartment and a lower compartment. The upper compartment is employed to contain the supply of unused toweling while the lower compartment is employed to contain the used or soiled portions of the toweling. The plate or partition 7 prevents any possible contact of the unused portions of the toweling with the soiled portions.

In assembling, the various rollers are introduced into the appropriate bearing apertures provided upon the walls 5 and 6 and the partition wall 7 is then fastened in place so as to retain the walls 5 and 6 against spreading. After this has been done the walls 5, 6 and 7, with the rollers carried thereby, are slid into the guideways 4 and fastened in place. The main casing thereafter serves to stiffen up the walls 5, 6 and 7 and to retain said walls rigidly in their proper and effective position.

The path of travel of the toweling through the device is as follows:

From the supply roller H downwardly around the rod 10, backwardly and around the friction roller 11, passing between said roller 11 and a co-operating friction roller 12, thence forwardly through an opening 13 in the door 3 and downwardly over a roller 14 providing the portion 15 ready for use, thence upwardly as at 16 and over a roller 17 returning into the casing through the lower part of the opening 13, beneath the

partition 7, around a roller 18 and backwardly to the take-up roller 19, being fed to the roller 19 by means of a co-operating rough faced roller 20.

The passage of the tape, or ribbon of toweling, about the roller 11 and between said roller and the roller 12, causes the roller 12 to rotate and to impart rotation, through a train of gears 21, 22 and 23, direct to the roller 20. The gear 21 is fixed to the end of the spindle 24 of the roller 12 and turns positively with said roller. The gear 22 is rotatably mounted upon the wall 6. The gear 23 is fixed to the outer end of the spindle 25 of the roller 20 to positively rotate said roller.

The spindles 24 and 25 of the rollers 12 and 20 project through the wall 6, and the gears 21, 22 and 23 are disposed and obscured from view within the space or compartment A formed between the wall 6 and the side wall of the main casing.

The surface of the roller 20 is roughened, as for instance by being supplied with a quantity of coarse sand cemented thereto. This roughened surface engages the surface of the toweling and causes the toweling to be fed on to the roller 19 as the roller 20 rotates.

In order to accommodate the change in diameter of the roll of toweling upon the roller 19, said roller is mounted upon a support which comprises a pair of spring pressed brackets 26 by means of which said roller is at all times resiliently pressed toward the roller 20.

The brackets 26 may be in any desired form, but preferably each comprises an elongated lever-like member, as best seen in Fig. 1, said members being pivotally connected to the inner surface of the plates 5 and 6, as at 27, and being resiliently urged upwardly by means of the tension springs 28. The spindles, as 29, of the roller 19 are received in seats 30 formed upon the upper surface of the members 26 preferably by means of a separate strip of metal 31 fixed to the member 26 and bent to provide said seat. The rear end of the members 31 may be bent as at 32 so as to form attaching means for the springs 28.

The forward end of the members 26 project to points near the forward edge to the casing and those portions of said members between their forward ends and the seats 30 constitute convenient and appropriate guide ways backwardly along which the spindles 29 of the roller 19 may be slid, toward the seats 30 for placing the roller in operative position.

At least one end of the roller 19 is fitted with a ratchet wheel 33, and a pawl 34 is carried by the adjacent member 26 for engaging the teeth of the ratchet to positively retain the roller 19 against rotating in an

unwinding direction. A light spring 35 is arranged for urging the pawl against the teeth of the ratchet, and a stop 36 is provided for engaging between the pawl and a portion of the member 26 to hold the pawl in an appropriate position for receiving the ratchet wheel when the roller 19 is being inserted.

5 The bearings for all of the gears 21, 22 and 23 are immovable relatively to each other and thus said gears are maintained in proper coöperative relation at all times.

10 The friction between the rollers 11 and 12 is preferably afforded by mounting the roller 11 so that it presses resiliently against the roller 12.

15 The support for the roller 11 therefore comprises a swinging frame made up of the cross rod 10 and a pair of members N, constructed as shown in Figs. 7 and 8. The members N are pivotally connected at their upper ends to the walls 5 and 6, as at 36, and the roller 11 is mounted in the bearings 37 formed at the lower ends of said 20 members to receive the spindles 38 of said rollers.

25 The rod 10 is fixed by its opposite ends to the members N so as to insure movement of said members in unison.

30 Each member N is formed of two parts pivotally connected together as at 39, said parts being disposed at an angle relative to each other. A spring 40 is carried by one of the parts and has one of its ends engaging the other part to force the parts in a direction to straighten the angle. One of the parts is provided with a shoulder 41 and the other part is provided with a heel 42 which engages the shoulder 41 to limit the 35 straightening movement of said parts.

40 By supporting the roller 11 upon this frame, the roller may be swung from an operative position within the casing to an inoperative position of accessibility outside of the casing, as suggested by the dotted lines 45 of Fig. 1.

When the roller is in its operative position within the casing, it stands in engagement with the upper surface of the roller 50 12, and the parts of the members N are bowed so that the heels 42 are moved away from the shoulders 41, and the force of the spring 40 is in full play to urge the roller 11 against the roller 12. It should be pointed out that, owing to the obtuseness of the angle formed by the two parts of the members N, only a comparatively light spring 55 is required to produce a very powerful pressure of the roller 11 against the roller 12.

60 The members N are preferably formed of sheet metal bent into U-cross section, and the springs 40 are arranged mostly within the space between the legs of the U, each spring being formed with a coil disposed 65 to engage about a cross pin 46 whereby to

retain the springs against displacement. The end portions, as 43, of the connecting rod 10, which portions bridge the space between the legs of the U, constitute bearing surfaces for receiving the pressure from the ends of the springs.

A pair of latch members 44 is provided, carried by the walls 5 and 6 one adjacent each of the members N, for engaging the rod 10 to releasably retain the roller 11 in its 70 operative position.

Suitable stops, as 45, are provided for limiting the inward movement of the lower end of the members N.

When the roller 11 is swung outwardly 80 so that it no longer engages the roller 12, the springs 40 cause the parts of the members N to straighten until the heels 42 engage the shoulders 41.

The friction grip of the rollers 11 and 12 85 with the material of the towel may be provided by any suitable means but is preferably provided by two sets of corrugated rubber rings or bands 47 and 48 carried respectively by the rollers 11 and 12, one adjacent each end of each of said rollers as best seen in Fig. 2. These rings afford a plurality of ridges against which the material of the toweling engages. In the case of the roller 11, the toweling makes almost 90 a complete turn about said roller, owing to the position of the cross rod 10, and the ridges materially improve the frictional grip of the toweling upon the roller.

Also the ridges of the rings upon the two 100 rollers coöperate with each other in gear-tooth fashion so that the interposed passing section of the toweling is caused to assume a corrugated form between the ridges of the two rollers. This improves the effectiveness of the toweling in rotating the rollers 11 and 12.

105 The rubber rings upon the roller 11 are fixed rigidly to said roller.

The rings upon the roller 12, however, are 110 not rigid but are so mounted and formed as to be adjustable so that the speed of rotation of the roller 12, and the consequent speed of rotation of the take-up roller 19 may be suitably altered at will.

115 In Figs. 5 and 6 is illustrated a simple, practical and highly efficient device for this purpose. The rings 48 are mounted upon a pair of semi-circular plates 49 which plates are received within an annular recess 50 120 formed in the roller. The adjacent ends of the plates are spliced together as shown at 51, and the marginal portions of the plates are flanged outwardly as at 52 to provide a more efficient seat to receive the rubber ring. At diametrically opposite points within the recess 50, a pair of screws 53 is provided, said screws having their heads, as 54, projected into openings 55 formed in the plates 49. The rubber ring 125 130

1
is provided with a pair of openings 56 in line with the openings 55. The openings 55 and 56 afford means of reaching the heads of the screws by means of a screw driver or other implement, but the openings 55 are smaller than the heads of the screws so that the screws cannot pass outwardly therethrough. Rotation of the screws in one direction, therefore will force the plates apart 10 and stretch the rubber ring.

Rotation of the screws in one direction will increase the circumferential measurement of the rubber ring while rotation in the contrary direction will allow the ring to contract and decrease said measurement.

Whenever it is found that the take-up roller 19 is taking up too much or too little of the toweling it is simply necessary to adjust the screws 53 in order to correct the 20 fault. It is seldom necessary to do this except when placing a new supply of toweling within the casing as practice has shown that the elements affecting the degree of rotation imparted to the take-up roller by the passage 25 of a given length of toweling between the friction rollers are mostly controlled by the texture and thickness, etc., of different toweling materials.

The roller 14 is preferably carried upon a 30 pair of arms 57 which are fixed to the walls 5 and 6 and which project outwardly through the opening 13 formed within the door 3 when the door is closed. The door may be swung to open or closed position without 35 interfering with the position of this roller.

The roller 17 is pivotally mounted upon the door to swing therewith.

The roller 18 is pivotally mounted upon the walls 5 and 6 and carries a pair of disks 40 58 adjacent its opposite ends which serve as guide means for engaging the opposite edges of the toweling to guide the toweling on to the take-up roller 19.

In threading the toweling into this device 45 the supply roll is first inserted into the position shown in Fig. 1. The spindles, as 59, thereof being moved along the guides 64 and disposed to engage seats 60 carried by the walls 5 and 6 at the rear end of the 50 guides. After the feed roller is correctly placed, the members N are swung outwardly to the position shown by the dotted lines in Fig. 1 and the end of the toweling is drawn outwardly and threaded straight down- 55 wardly between the rod 10 and the adjacent surface of the roller 11, it of course being understood that the door 3 is now swung open. The end of the toweling is then wound for one or more turns about the roller 60 19 which at this time is held loosely in the operator's hand. After the end of the towel has been connected with the roller 19, in approximately the position shown in Fig. 1, said roller is then moved directly into the 65 casing so that its spindles slide along the

upper surface of the members 26 and 31 and snap into the seats 30.

The roller 11, is then swung inwardly to approximately its operative position but not so far as to stand in final forced engagement with the roller 12.

Sufficient toweling is then drawn from the supply roller H to afford the desired length 15 and 16 for use, and the roller 11 is then forced to its final position in engagement with the roller 12. The latches 75 44 are set, and the door is closed.

Thereafter the operator has simply to draw out upon the lead 15 and this action will automatically rotate the take-up roller 80 19 and maintain the exposed portions 15 and 16 substantially unchanged throughout repeated use.

It will be seen that the threading operation is direct and simple and yet that when 85 the parts are moved into the operative position after threading the toweling is carried into proper co-operative engagement with the movable elements of the device.

Any suitable means, as for instance, the 90 springs 61 may be employed for affording friction to resist undesirable rotation of the feed roller, as will be readily understood.

It is to be noted that the seats 60 for the spindles 59 of the feed roller are of a de- 95 cidedly different size from that of the seats 30 for the spindles of the take-up roller 19. This is an intentional provision against the possibility of interchanging of the rollers by unscrupulous users who might seek to 100 place the feed roller in the position of the take-up roller, and vice versa, after the toweling has been once fed wholly on to the take-up roller. By means of this provision, he is restrained from making repeated use 105 of the toweling.

In Figs. 9 and 10 is illustrated a bearing which is admirably adapted for use in supporting certain of the rollers in this device. This bearing includes an off-set, or saucer-like, member 62 which is held in position against one of the walls 5 and 6 by means of a thimble 63. The thimble serves to retain the member 62 and the member 62 serves to support the thimble. The thimble may 110 thus be given an appreciable length and may be made of suitable material, such as brass, for affording an ideal and cheap type of bearing for receiving the roller spindles.

It has been found in practice that the 115 momentum gathered in the inwardly moving towel at times causes it to sag down away from the roller 18 and away from the guide flanges 58. Means is therefore provided to prevent this, as follows:

The reference character 65 indicates a pivotally mounted friction member which is arranged adjacent the roller 17 for engaging against the towel just where the towel enters the lower compartment of the casing. 130

Suitable teeth 66 are provided upon that portion of the member 65, which engages the towel for rubbing against the rough surface of the woven fabric to improve the frictional engagement, and said teeth are spaced from the adjacent inner surface portion 67 of the door 3, so as to exert a light but constant pressure upon the inner surface of the towel sufficient to prevent any portion of the 10 towel from moving inwardly except as it is positively drawn in by the take-up roller. The ears, as 68, at the opposite ends of the friction member are pivotally mounted upon the walls 5 and 6.

15 In order to prevent rotation of the roller 11 without a rotation of the roller 12, these rollers are fitted with intermeshing gears 69 and 70 respectively. The teeth of these two gears preferably have a loose fit so as not to 20 interfere with the swinging movement of the roller 11 in the frame N. The particular object of gearing the roller 11 and 12 together is to prevent likelihood of the towel being drawn outwardly from between said 25 rollers at any time without an accompanying rotation of the take-up roller 19. The great extent of the engagement of the towel with the rubber rings 47 of the roller 11, afforded by the position of the rod 10, effectively 30 avoids opportunity for a movement of the towel without imparting rotation to the roller 11. In order, however, to more positively insure rotation of the roller 11 with the movement of the towel, said roller 35 is provided with one or more toothed bands 71 disposed intermediate the rubber rings 47. The teeth of these bands project radially from the roller to a circular plane just inside of the ends of the teeth on the rubber 40 rings so that during the normal operation of the device the teeth of the bands 71 perform little or no function. But when an undue strain is applied to draw the towel outwardly between the rollers 11 and 12 45 while preventing rotation of the roller 12, (as by holding the lead 16 of the towel against return movement) the material of the towel is naturally caused to bow inwardly between the rubber rings 47 so as to 50 press against the teeth of the bands. The teeth are so disposed, as indicated by the fragmentary section of one of the bands shown in Fig. 1, as to bite into the towel and almost positively prevent movement of 55 the towel without imparting corresponding rotation to the roller.

It should here be pointed out that the adjustment of the diameter of the bands 48 is only slight and that the consequent alteration in the degree of rotation imparted to the rollers 11 and 12 by the passing of a given length of the towel is very minute. In fact, the alteration is so slight that the co-operation of the resilient surfaces of the

bands with the resilient material of the 65 towel itself readily accommodates it without producing any apparent slippage of the towel relatively to the rollers such as might naturally be looked for in view of the fact that the rollers are geared together. 70

Since it is possible that the roller 20 may be made to rotate without producing corresponding rotation of the take-up roll, this invention comprises means for preventing such an eventuality, as follows: 75

At least one end of the roller 18 is mounted in an elongated bearing 72 arranged in such manner as to permit an upward movement of the adjacent end of the roller 18 whenever the lead 16 is held back. A lever 80 73 is pivotally mounted upon the wall 6, as at 74. One end of this lever lies above the spindle 75 of the roller 18 while the opposite end is provided with a tooth 76 arranged to engage the teeth of the gear 23. The lever 85 is normally held, by a spring 77, in a position with the tooth 76 out of engagement with the gear. When, however, the spindle 75 is moved upwardly the lever is swung so that the tooth engages the gear 90 and positively prevents any rotation of the gear until the lever is allowed to return to its normal position.

It will thus be seen that means is provided for positively insuring against withdrawal of any portion of the towel from the feed roller H without a corresponding "take-up" action by the take-up roller. Thus the length of the exposed portion of the towel, after having been once determined as above described, is maintained without change until all of the toweling on the supply roller has been withdrawn. 100

In order to render the guide disks 58, which are carried upon the roller 18, more 105 effective for their purpose, these guide disks are preferably separately formed and adjustably mounted longitudinally of the roller. They may be moved to form proper 110 guide relation with different widths of toweling. This is very important particularly because of the fact that different toweling materials have different shrinkage at different times according to the method by which it is washed. 115

The particular manner of rendering the disks 58 adjustable may be modified but the manner illustrated includes forming each of said disks from a piece of sheet metal. Central apertures are provided for receiving the 120 roller, and the material of the disk displaced in the formation of the apertures is bent outwardly to provide a series of spring fingers 78 disposed to press toward a common center in such manner as to provide a very 125 effective grip upon the roller. The roller is preferably made of wood so as to better co-operate with the fingers 78. The outer an-

nular edge portions of the disks are bent laterally, as at 79, so as to avoid catching the material of the towel.

A lock, as 80, is preferably arranged between the door 3 and the casing for retaining the door closed during the normal use of the device.

As many changes could be made in this construction without departing from the scope of the following claims, it is intended that all matter contained in the above description, or shown in the accompanying drawings, shall be interpreted as illustrative only and not in the limiting sense.

Having thus described my invention what I claim as new and desire to secure by Letters Patent, is:

1. In a device of the class described, a movable tape, mechanism to be operated by the movement of said tape, means whereby the movement of said tape will operate said mechanism comprising a pair of rollers between which the tape moves, and means for altering at will the circumferential measurement of that portion of at least one of said rollers which engages the tape.

2. In a device of the class described, a movable tape, mechanism to be operated by the movement of said tape, means whereby the movement of said tape will operate said mechanism comprising a pair of rollers between which the tape moves, means operatively connecting one of said rollers with said mechanism, and means whereby the rotary movement imparted to said mentioned roller by the passage of a given length of tape may be altered at will.

3. In a device of the class described, a movable tape, mechanism to be operated by the movement of said tape, means whereby the movement of said tape will operate said mechanism comprising a pair of rollers between which the tape moves, means operatively connecting one of said rollers with said mechanism, and means whereby the circumferential measurement of that part of said mentioned roller which engages the tape may be increased or diminished at will.

4. In a device of the class described, a movable tape, mechanism to be operated by the movement of said tape, means whereby the movement of said tape will operate said mechanism comprising a pair of rollers between which the tape moves, means operatively connecting one of said rollers with said mechanism, and means whereby the rotary movement imparted to said mentioned roller by the passage of a given length of tape may be altered at will, comprising a friction ring carried by said roller for engaging the tape, and means for adjusting the circumferential measurement of said ring.

5. In a towel holder, the combination with a strip of towel material, towel take-up

mechanism to be operated by the movement of said towel, and means whereby the movement of said towel will operate said take-up mechanism, of means whereby the effect upon said take-up mechanism of the passage of a given length of said towel may be adjusted at will.

6. A towel holder, comprising a feed roll for containing a strip of towel material wound thereon, a take-up roll for receiving the used portion of said towel, and drive means for the take-up roll comprising in part a pair of friction rollers between which the towel moves from the feed roll to the take-up roll, and means whereby the effect upon the drive means of the passage of a given length of the towel between said friction rollers may be altered at will.

7. A towel holder, comprising a feed roll for containing a strip of towel material wound thereon, a take-up roll for receiving the used portion of said towel, and drive means for the take-up roll, said drive means comprising in part a pair of friction rollers between which the towel moves from the feed roll to the take-up roll, and means whereby one of said rollers is bodily movable into and out of co-operative relation with the other of said rollers to facilitate threading of the towel between said rollers.

8. A towel holder, comprising a feed roll for containing a strip of towel material wound thereon, a take-up roll for receiving the used portion of said towel, and drive means for the take-up roll comprising in part a pair of friction rollers between which the towel moves from the feed roll to the take-up roll, and a swinging frame upon which one of said rollers is carried whereby said roller may be bodily swung into and out of co-operative relation with the other of said rollers to facilitate threading of the towel between said rollers.

9. A towel holder, comprising a feed roll for containing a strip of towel material wound thereon, a take-up roll for receiving the used portion of said towel, and drive means for the take-up roll comprising in part a pair of friction rollers between which the towel moves from the feed roll to the take-up roll, a swinging frame upon which one of said rollers is carried whereby said roller may be bodily swung into and out of co-operative relation with the other of said rollers to facilitate threading of the towel between said rollers, and means for retaining the frame in one of its positions.

10. A towel holder, comprising a feed roll for containing a strip of towel material wound thereon, a take-up roll for receiving the used portion of said towel, and drive means for the take-up roll comprising in part a pair of friction rollers between which the towel moves from the feed roll to the take-up roll, a swinging frame upon which

one of said rollers is carried whereby said roller may be bodily swung into and out of coöperative relation with the other of said rollers to facilitate threading of the towel between said rollers, and a latch for retaining the frame in a position with the roller in operative position.

11. A towel holder, comprising a feed roll for containing a strip of towel material wound thereon, a take-up roll for receiving the used portion of said towel, and drive means for the take-up roll, said drive means comprising in part a pair of friction rollers between which the towel moves from the feed roll to the take-up roll, means for resiliently urging one of said rollers toward the other, and means whereby one of said rollers is bodily movable into and out of coöperative relation with the other roller.

12. In a device of the class described, a movable tape, mechanism to be operated by the movement of said tape, and means whereby the movement of said tape will operate said mechanism comprising a pair of rollers between which the tape moves, said rollers having mating relatively raised and depressed portions for frictionally engaging the tape, means whereby one of said rollers is bodily movable into and out of coöperative relation with the other roller to facilitate threading of the tape between said rollers, and means resiliently urging one of said rollers toward the other.

13. A towel holder, comprising a feed roll for containing a strip of towel material wound thereon, a take-up roll for receiving the used portion of said towel, and drive means for the take-up roll comprising in part a pair of friction rollers between which the towel moves from the feed roll to the take-up roll, and a swinging frame upon which one of said rollers is carried whereby said mentioned roller may be swung free of the other roller to provide a wide open space between said rollers through which the towel may be readily threaded, said frame also constituting means whereby the roller may be swung again into coöperative engagement with the other roller so as to carry the towel into frictional engagement with said other roller.

14. A towel holder, comprising a feed roll for containing a strip of towel material wound thereon, a take-up roll for receiving the used portion of said towel, and drive means for the take-up roll comprising in part a pair of friction rollers between which the towel moves from the feed roll to the take-up roll, and a swinging frame upon which one of said rollers is carried whereby said mentioned roller may be swung free of the other roller to provide a wide open space between said rollers through which the towel may be readily threaded, said frame also constituting means whereby the roller may

be swung again into coöperative engagement with the other roller so as to carry the towel into frictional engagement with said other roller, and means for resiliently urging one of said rollers toward the other when said mentioned roller is in said last referred to position.

15. A towel holder, comprising a feed roll for containing a strip of towel material wound thereon, a take-up roll for receiving the used portion of said towel, and drive means for the take-up roll comprising in part a pair of friction rollers between which the towel moves from the feed roll to the take-up roll, and a swinging frame upon which one of said rollers is carried whereby said mentioned roller may be swung free of the other roller to provide a wide open space between said rollers through which the towel may be readily threaded, said frame also constituting means whereby the roller may be swung again into coöperative engagement with the other roller so as to carry the towel into frictional engagement with said other roller, and means comprised in said frame adapted to urge the mentioned roller into yielding engagement with the other roller when the mentioned roller is in the last referred to position.

16. A towel holder, comprising a feed roll for containing a strip of towel material wound thereon, a take-up roll for receiving the used portion of said towel, and drive means for the take-up roll comprising in part a pair of friction rollers between which the towel moves from the feed roll to the take-up roll, and a support for one of said rollers comprising means for urging said mentioned roller toward the other roller, and means whereby said support may be moved to dispose said mentioned roller entirely out of engagement with the other roller.

17. A towel holder, comprising a supply from which a strip of towel material may be drawn for use, take-up means for taking up the used portion of the towel, drive means for driving the take-up means, said drive means comprising in part a drive roller, means whereby the drive roller is bodily movable from an inoperative position, in which the towel may be readily threaded therebehind, into an operative position carrying the towel into frictional engagement therewith, and an auxiliary roller about which the towel is carried to improve the frictional engagement of the towel when said drive roller is moved into operative position.

18. In a towel holder, a pair of detachable rollers one for containing the unused towel and the other for receiving the used portions of the towel from the first roller, independent supports for said rollers, means whereby the support for one roller is resiliently

- mounted, and means carried by said support for engaging a part carried by the mentioned roller whereby to retain the mentioned roller against rotation except in one direction.
19. A towel holder, comprising a casing adapted to contain a supply of unused toweling material and also to receive the used portion of the towel material, said casing having an opening in one wall thereof through which the towel may move into and out of the casing, a roller supported adjacent the opening exteriorly of the casing over which the unused portion of the towel may be drawn outwardly from the casing, and beneath which the used portion of the towel may pass through said opening into the casing, and a partition arranged within the casing adjacent said opening dividing the casing into two compartments from one of which compartments the toweling is adapted to feed outwardly from said opening and into the other of which compartments the toweling is adapted to feed inwardly through said opening.
20. A towel holder, comprising a casing having a door to close one side thereof, said casing being adapted to contain a supply of unused toweling material and also to receive the soiled portions of the towel material, a roller supported exteriorly of the casing over which the unused portion of the towel may be drawn outwardly from the casing, the door being formed with an opening adjacent the roller whereby to permit passage of the roller outwardly with respect to the door when the door is moved to closed position, said opening serving also to accommodate passage of the unused towel material outwardly from the casing to the roller and serving also to permit passage of the used portion of the towel material backwardly into the casing, and a partition arranged within the casing adjacent said opening disposed to divide the casing into two separated compartments each communicating with said opening.
21. In a towel holder, a pair of detachable rollers one for containing the unused towel and the other for receiving the used portions of the towel from the first roller, independent supports for said rollers, said supports having seats formed therein, said rollers having spindles for engaging said seats, and the seats for the spindles of one roller being of a character not to accommodate the spindles of the other roller, for the purpose set forth.
22. In a towel holder, a part adapted to contain a quantity of toweling for use, take-up means for receiving the used portions of the toweling, and a friction member for engaging the toweling adjacent the take-up means whereby to maintain a desirable tension upon the toweling entering the take-up means, and gripping teeth formed upon the portion of the friction member which engages the toweling.
23. In a towel holder, a part adapted to contain a quantity of toweling for use and from which the toweling may be readily drawn, a take-up roller for receiving the used portions of the toweling, means whereby the drawing of the toweling from said mentioned part will rotate the take-up roller, and a friction member disposed to engage the toweling just prior to entrance of the toweling onto the take-up roll adapted to frictionally prevent passage of any portion of the toweling toward the take-up roller except under the positive pull of the take-up roller.
24. In a towel holder, a part adapted to contain a quantity of toweling, a take-up roll for receiving the used portions of the toweling, a roller over which the toweling passes to said take-up roll, drive means whereby movement of the toweling from the first mentioned part will drive the take-up roll, and means operative to positively prevent operation of the drive means in the presence of a strain tending to prevent the feeding of the used portions of the toweling to the take-up roll.
25. In a towel holder, a part adapted to contain a quantity of toweling for use, a take-up roll for receiving the used portions of the toweling, drive means whereby movement of the toweling from the first mentioned part will drive the take-up roll, a roller over which the toweling passes to the take-up roll, said roller being at least in part bodily displaceable when an undue tension is applied to prevent movement of the toweling to the take-up roll, and means extending from said roller to said drive means adapted to be operated by the displacement of the roller to positively prevent operation of the drive means.
26. In a device of the class described, a movable tape, mechanism to be operated by the movement of the tape, means whereby normal movement of the tape will operate said mechanism comprising a pair of rollers between which the tape moves, at least one of said rollers having a relatively depressed annular portion thereon over which the tape bridges during the normal movement of the tape but into which the tape sinks when strain is applied thereon, and means arranged in said relatively depressed annular portion to be engaged by the tape to positively transmit the movement of the tape to the roller.
27. In a device of the class described, a movable tape, a mechanism to be operated by the movement of the tape, means whereby the movement of the tape will operate said mechanism comprising a pair of rollers between which the tape moves, intermeshing gears carried one by each of said rollers

whereby to insure simultaneous rotation thereof, means whereby the normal movement of the tape will cause rotation of both rollers, connections from one of said rollers 5 to the mechanism to be operated, and auxiliary means whereby abnormal forced movement of the tape will insure rotation of the other roller.

28. In a towel holder, the combination comprising a movable strip of towel material, 10 take-up mechanism to be operated by the movement of said towel, means whereby movement of said towel will operate said take-up mechanism comprising a pair of rollers between which the towel moves, and 15 means providing a series of resilient longitudinally extending ridges and grooves upon said rollers between which the towel moves, for the purpose set forth.

29. A towel holder comprising a casing 20 made up of an inner member and an outer member, the inner member being of general H-shape providing a pair of side walls spaced apart adapted for receiving and supporting various elements of mechanism and 25 a cross wall connecting the side walls together, the outer member being adapted to receive the inner member therein and to supplement the action of said cross wall 30 for holding said side walls in proper co-operative relation with said mentioned elements of mechanism, and said cross wall being disposed so that when within the outer member it constitutes a horizontal partition 35 dividing the casing into upper and lower compartments.

30. A towel holder comprising a casing made up of an inner member and an outer member, the inner member being of general 40 H-shape providing a pair of side walls spaced apart adapted for receiving and supporting various elements of mechanism and

a cross wall connecting the side walls together, the outer member being adapted to receive the inner member therein and to supplement the action of said cross wall for holding said side walls in proper co-operative relation with said mentioned elements of mechanism, and said cross wall being disposed so that when within the outer member 45 it constitutes a horizontal partition dividing the casing into separate compartments, together with tangs carried by the inner member adapted to extend through openings formed in the outer member and 50 to be bent into retaining position beyond said openings to thereby retain the inner member within the outer member.

31. A towel holder comprising a casing made up of an inner member and an outer 60 member, the inner member comprising a pair of side walls spaced apart and a connecting wall for holding the side walls together, a plurality of rollers extending between said side walls pivotally mounted in 65 openings formed in said side walls, the outer member being adapted to receive the inner member therein and to supplement the action of said connecting wall for holding said side walls in proper co-operative relation 70 with said mentioned rollers, gears arranged beyond one of said side walls connecting certain of said rollers together, and said mentioned side wall being adapted when 75 within said outer member to co-operate with an adjacent wall of said outer member for forming a compartment separated from said rollers to contain said gears.

In testimony whereof I affix my signature in the presence of two witnesses.

WADE W. BOWMAN.
